J. C. BEAM

TRAFFIC INDICATOR

Filed Nov. 26, 1921

FIG. 4.

Inventor

J.C. Beam

By Attorney

Patented May 12, 1925.

1,537,288

UNITED STATES PATENT OFFICE.

JACOB C. BEAM, OF PHILLIPSBURG, NEW JERSEY.

TRAFFIC INDICATOR.

Application filed November 26, 1921. Serial No. 517,874.

To all whom it may concern:

Be it known that I, JACOB C. BEAM, a citizen of the United States, residing at Phillipsburg, in the county of Warren and 5 State of New Jersey, have invented certain new and useful Improvements in Traffic Indicators; and I do hereby declare the following to be a full, clear, and exact description of the invention, such as will enable 10 others skilled in the art to which it appertains to make and use the same.

This invention has relation to signals designed chiefly for use in connection with motor vehicles, whereby to indicate the intention of the driver when about to stop or 15 to turn to the right or left, so that drivers of following vehicles and those approaching may govern themselves accordingly and obviate confusion and accidents.

20 The signal is constructed so that one may be disposed at the front of the machine or vehicle and one in the rear thereof, both signals being operated simultaneously to give a like indication both at the front and 25 in the rear of the machine, each device containing a pair of electric lamps which are included in independent circuits, and each of the circuits having a switch for making and breaking the circuit as required.

30 Other objects and advantages will be apparent and suggest themselves as the nature of the invention is understood.

While the drawings illustrate an embodiment of the invention, it is to be understood 35 that in adapting the same to meet different conditions and requirements, various changes in the form, proportion and minor details of construction may be resorted to without departing from the nature of the 40 invention.

Referring to the accompanying drawings forming a part of the application,

Figure 1 is a perspective view of a signal embodying the invention,

45 Figure 2 is a horizontal section on the line 2—2 of Figure 1,

Figure 3 is a cross section on the line 3—3 of Figure 1, and

50 Figure 4 is a detail perspective view of one of the indicating ends.

Corresponding and like parts are referred to in the following description and designated in the several views of the drawings by like reference characters.

55 The signal embodies a box 1 which is open

at opposite ends and has portions cut from the front of opposite ends as indicated at 2. A partition 3 is disposed midway the ends of the box and forms end chambers. The partition 3 is provided upon opposite sides with sockets 4 which are adapted to receive lamp bulbs 5. Lead wires 6 have connection with the sockets 4 in the usual way so as to supply current to the lamps 5. The box 1 preferably consists of sheet metal and 60 may be of any desired proportions.

An indicating end 7 is fitted to each end of the box 1 and preferably consists of glass and is hollow, the front wall of the glass being flat and having a groove 6^a to accommodate the adjacent wires 6 whereas the rear wall is curved and merges into the top and bottom walls, whereby to provide a reflecting surface which is silvered or otherwise coated to reflect rays of light and project the same through the front wall. The outer portion of the end 7 is frosted or otherwise prepared so as to diffuse the rays of light with the exception of a portion of the front, which is transparent so as not to 70 obstruct the rays of light projected therethrough. The transparent portion of the front wall of the part 7 conforms to the outline of an arrow as indicated at 8, said arrow being disposed to point outwardly 75 whereby to indicate the direction of turn when illuminated. The inner portion of the indicating end 7 is connected with the box 1 by means of a slip joint and the front wall covers the cut-away portion 2 of the 80 box. Indentations 9 are formed in the upper and lower walls of the indicating end 7 and receive the inner ends of screws 10 which are threaded into the top and bottom of the box 1. In this manner, the indicating 85 ends 7 are retained in place.

The box is provided with a suitable clamp 11 or other attaching means whereby it may be connected to a suitable portion of the vehicle, such as the filling tube of the radiator 100 or a bracket. Small openings 12 are formed in the back of the box 1 opposite the lamps 5 so that it may be readily ascertained whether the lamps are lighted or not.

In assembling the device, the lamp 105 sockets 4 are first applied to the partition 3 with the lead wires 6 extending through suitable outlets in the base wall of the box 1. The lamps or bulbs 5 are then applied after which the signal ends are inserted 110

or telescoped into the box at the opposite ends thereof and thereafter fastened by the elements 10.

In practice, one of the devices is located at the front of the machine and one in the rear thereof, and corresponding lamps are included in the same circuit so that when the driver is about to make a turn to the right both the front and rear lamps on the right hand side of the vehicle are lighted and if the turn is to be to the left, the front and rear lamps on the left hand side of the machine are lighted. When the driver is about to stop both sets of lamps are lighted, thereby indicating that no turn is to be made but that the vehicle is about to be brought to a standstill. The switch for controlling the circuit may be of any preferred type and may be disposed upon the steering wheel or other convenient part of the machine so as to be readily accessible by the driver.

What is claimed is:

An indicator of the class described comprising an open ended substantially rectangular casing and having an integral partition therein intermediate of its ends, a socket for the reception of a lamp secured

to each side of said partition, the front portion of said casing being partly cut away on each side of said partition to provide openings for the radiation of light therethrough, an indicating member inserted into each end of the casing and consisting of a hollow body of light penetrable material, said members being formed to fit the ends of the casing and each having an opening in its inner end to receive the sockets referred to, the front wall of each member being flat and having a transparent indicating device thereon partly exposed by the cut away portions of the casing, the remainder of the front of the indicating member being formed to diffuse light rays, the top, bottom and rear walls of the indicating member not covered by the casing being curved and merging into the front wall and provided with a light reflecting surface.

In testimony whereof I affix my signature in presence of two witnesses.

JACOB C. BEAM.
